DESIGN FOR A FOREMAN'S SERVICE DESK

Walter L. Borroughs, Kalamazoo, Mich., assignor to Borroughs Manufacturing Company, Kalamazoo, Mich.

Application December 12, 1940, Serial No. 97,279

Term of patent 3½ years

To all whom it may concern:

Be it known that I, Walter L. Borroughs, a citizen of the United States, residing at Kalamazoo, in the county of Kalamazoo and State of Michigan, have invented a new, original, and ornamental Design for a Foreman's Service Desk, of which the following is a specification, reference being had to the accompanying drawing, forming part thereof, wherein the figure is a perspective view of a foreman's service desk embodying my new design.

The rear of the desk is plain and the opposite side is substantially similar to the side shown.

I claim:

The ornamental design for a foreman's service desk, as shown and described.

WALTER L. BORROUGHS.
